HANDY MEMO

Samuel Segal, New York, N. Y., assignor to Wilson-Jones Co., Chicago, Ill., a corporation of Massachusetts

Application August 30, 1948, Serial No. 46,839

4 Claims. (Cl. 281—19)

1

This invention is a handy memorandum pocket notebook and especially is directed to a novel and improved strap fixedly mounted on the inside of the cover of the notebook for appropriately retaining the pad thereon. One object of the invention is to provide a practical and effective retaining strap having keeper means embodying suitable prongs for penetrating inwardly turned marginal flanges or lips of the cover, whereby the retaining strap or bar is securely anchored widthwise of and within the cover. Another significant object is realized in the provision of a simplified pad retaining bar substantially coextensive with the width of the cover which embodies laterally extending flanges adapted to straddle and be foldable over and closely against outer marginal portions of the bar to overlap the latter, and adapted to be held thereagainst by the aforementioned prongs. Other important objects, advantages, and functional and structural features of the invention will be in part obvious and in part hereinafter more particularly pointed out in the following detailed description considered in the light of the accompanying drawings wherein:

Fig. 1 is a perspective view of the handy memorandum notebook according to my invention, illustrating the cover open to provide for convenient access to the removable pad.

Fig. 2 is a view similar to Fig. 1, but with the pad removed and illustrating the pad retaining bar anchored to the turned in flanges of the cover.

Fig. 3 is a perspective view of the cover shown open and with the retaining strap or bar mounted thereon but unsecured by the laterally extending flanges of the cover.

Fig. 4 is a fragmentary view of Fig. 3 illustrating the flanges bent inwardly over the outer marginal portions of the strap prior to securing the keeper means thereto.

Fig. 5 is an enlarged sectional view on the line 5—5 of Fig. 2.

Fig. 6 is a plan view of the retaining strap or bar shown in Fig. 3.

Fig. 7 is an elevational view of the strap taken on the line 7—7 of Fig. 6.

Fig. 8 is an enlarged fragmentary view of Fig. 5, and

Fig. 9 is a lengthwise sectional view on the line 9—9 of Fig. 1.

The handy memorandum notebook is generally designated HM and is characterized by the retaining strap or bar B seated widthwise of and within the cover broadly denoted C. Specifically

2

the bar B is substantially coextensive with the width of the lower component or backing 10 of the substantially rectangularly shaped cover and is preferably positioned near the upper margin of the backing. As shown, the front component or closure 11 of the cover is integral with the backing 10 and is adapted to be swung away from or towards the latter to render the pad PD accessible for making entries thereon or to protect the pad. The cover may be of a suitable leather, plastic, paper or of any other fairly flexible material, and preferably of a size adapted to conveniently fit into a small pocket.

Referring again to the backing 10, it will be observed that flanges F (Fig. 3) are integral therewith and extend laterally therefrom to overhang the sides of the backing and adjacent and laterally aligned with the relatively thin metal bar or strap B which is mounted on said backing.

Thereafter these flanges are bent upwardly to straddle the sides of the backing, then inwardly and downwardly to be closely arranged against and overlap the outer marginal portions 13 of the retaining bar B. The retaining bar B embodies struck out and normally upstanding spaced lugs or keeper means generally indicated K, each provided with spaced corner prongs P preferably angularly disposed substantially normal to the body of the respective keeper means as illustrated.

The bar B is mounted on the backing 10 and the flanges F folded upwardly, inwardly and downwardly against the marginal portions 13 to straddle the ends of the latter (Fig. 4). Thereafter both keeper means are bent downwardly against these marginal portions whereby the corner prongs P penetrate into the flanges F (Figs. 5 and 8) and effectively secure and anchor these flanges against the marginal portions 13. Moreover the folded and anchored flanges F cover these marginal portions to prevent accidental cutting of the hands of the user which may take place due to burrs or sharp edges.

With the bar fixedly retained on the backing 10 as described, the bound paper pad PD may be held thereby. In this connection the back supporting sheet 14 of the pad is threaded into the gap G (Figs. 5 and 9), formed between the backing 10 and bar B, until the line of stitches as 45 securing sheets S and back support sheet 14 together is met, thereby suspending the pad in place. To facilitate tearing of the sheets S from the pad the latter is provided with the line of perforations 16.

By the present structural arrangement the

pad may be quickly mounted on and retained by the bar, and when used up may be conveniently removed and readily replaced.

Various changes may be made in details of construction and arrangement of parts without departing from the spirit of the invention or sacrificing any of the advantages thereof inherent therein.

I claim:

1. In a memorandum pad support, a backing, a bar mounted on said backing and disposed widthwise thereof, flange means in part projecting upwardly of opposite edges of said backing to straddle the ends of said bar and in part disposed inwardly against outer marginal portions of said bar to overlap the latter, keeper means struck out of said bar and integral therewith and bent downwardly and against said flanges in their overlapping relation against said marginal portions, and prong means extending from said keeper means for penetrating into said flanges in said overlapping relation for anchoring said flanges against said marginal portions.

2. In a memorandum pad support, a backing, a bar substantially coextensive with the width of and mounted on said backing, flange means integral with said backing and in part projecting upwardly of opposite edges thereof to straddle the ends of said bar and in part disposed inwardly against outer marginal portions of said bar to overlap the latter, keeper means struck out of said bar and integral therewith and bent downwardly and against said flanges in their overlapping relation against said marginal portions, and prong means extending from said keeper means for penetrating into said flanges in said overlapping relation for anchoring said flanges against said marginal portions.

3. In a memorandum pad support, a backing, a bar mounted on said backing and disposed widthwise thereof, flange means in part projecting upwardly of opposite edges of said backing to

straddle the ends of said bar and in part disposed inwardly against outer marginal portions of said bar to overlap the latter, keeper means struck out of said bar and integral therewith and bent downwardly and against said flanges in their overlapping relation against said marginal portions, and prong means extending from spaced corners of said keeper means and substantially normal thereto for penetrating into said flanges in said overlapping relation for anchoring said flanges against said marginal portions.

4. In a memorandum pad support, a backing, a relatively flat bar substantially coextensive with the width of and mounted on said backing and inside thereof, flange means in part projecting upwardly of opposite edges of said backing to straddle the ends of said bar and in part disposed inwardly against outer marginal portions of said bar to overlap the latter, keeper means struck out of said bar and integral therewith and bent downwardly and against said flanges in their overlapping relation against said marginal portions, and spaced prong means depending at an angle from said keeper means for penetrating into said flanges in said overlapping relation for anchoring said flanges against said marginal portions.

SAMUEL SEGAL.
